¹² Joseph Vidina INVENTOR

BY

Erich S. Michaelis
his ATTORNEY.

UNITED STATES PATENT OFFICE.

JOSEPH VIDINA, OF CHICAGO, ILLINOIS.

WINDOW.

Application filed July 26, 1926. Serial No. 124,790.

The invention relates to windows for dwellings, residences and the like, and the object of the invention is to provide a window which may be opened and closed in the conventional manner of sliding the sashes of said window upwardly and downwardly respectively and which may at the same time be opened by swinging said sashes about vertical hinges.

10 A further object of the invention is to provide such window with a mechanism, whereby one of the counterweights usually attached to the movable window sash may be selectively connected to said sash or to 15 the stationary window frame.

Other objects of the invention not specifically mentioned may be easily ascertained and understood from the following specification and the accompanying drawings forming a part thereof.

In the drawings:

Fig. 1 is an elevation of a window according to the invention, a portion of the window frame being broken away to show the 25 construction of a part of the transfer mechanism.

Fig. 2 is a horizontal cross section on line 2—2 of Fig. 1.

Fig. 3 is a detail drawing in a larger scale 30 of the holder plate of the transfer mechanism.

Fig. 4 is an enlarged view of the transfer mechanism.

Fig. 5 is a section on line 5—5 of Fig. 4. 35 The window has a stationary frame 6 and two sashes 7 and 8 respectively, which are adapted to be slidably moved in said frame. The frame may be of any suitable construction, as long as it is provided with the usual 40 vertical guiding grooves 9, 10, 11, and 12 respectively. Pulleys 13, 14, 15, and 16 are rotatably mounted in said frame, and cables 17, 18, 19, and 20 are trained over the respective pulleys. Counterweights 21, 22, 45 23, and 24 are fastened one to each outer end of one of said cables. The inner ends of the cables 17 and 18 are fastened to the upper and lower movable window sash respectively.

50 The inner ends of the cable 19 and the cable 20 are fastened each to one holder plate 25. The sash frames are provided at their vertical outer rims with grooves adapted to receive the respective cables. Guide 55 plates 26 and 27 are provided on the sash

frames 7 and 8 respectively on that side of said sashes on which the cables 17 and 18 are fastened. Said guide plates 26 and 27 are adapted to engage the guide grooves 10 and 9 respectively. Female hinge parts 28 and 29 are provided on each of said sash frames on the above identified side thereof. Corresponding male hinge parts are fastened to stationary frame in such a manner, that the female hinge parts on the lower sash 7 are in engagement with the corresponding male hinge parts, when the sash is in its lowermost position in the stationary frame, i. e. in closed position. The other set of male hinge parts are fastened to the stationary frame in such a manner as to engage the female hinge parts on the upper sash, when said sash is slid down to its lowermost position in the stationary frame, i. e. when said sash is in open position.

55 The construction of the mechanism provided on the sash frame on the side opposite to the hinges is for both sashes the same, and only one such mechanism will be described therefore.

The sash frame is somewhat hollowed out to receive the mechanism described in the following, and a finishing board 32 covers said mechanism, with the exception of a cylinder 33, which is rotatably arranged in 60 the sash frame and extends into a hole (not shown) provided therefor in the finishing board. Said cylinder has in its uncovered end a polygonal hole 34 adapted to receive a correspondingly shaped removable key 65 (not shown) for rotating said cylinder. An arm 35 is rigidly connected to the cylinder, and a link 36 is pivotally jointed to said arm. A lever 37 is pivotally mounted on said link, the connection being effected intermediate the ends of said lever. A plate 38 is fastened to the sash frame, and one end of the lever 37 is fastened pivotally to said plate. The other end of said lever is pivotally connected to a flat guiding bar 39 adjacent the one end thereof. A lever 40 is pivotally connected to the bar 39 adjacent the other end thereof, and the lever 40 is pivotally connected with its other end to a plate 41 fastened to sash frame. By rotating said cylinder in one direction the flat bar 39 will be projected into engagement with the guide groove 12 or 11 respectively according to which sash the mechanism is attached to, and by rotation of the cylinder 105 110 115

in the other direction the guide bar will be retracted, so that the sash will be disengaged from the stationary frame.

As stated above the inner ends of the cables 19 and 20 are fastened each to a holder plate 25. As long as the sash is in position for sliding movement in the stationary frame, the holder plate is in engagement with a hook 42 fastened to the sash. For this purpose the plate has a rectangular opening 43 therein adapted to receive the hook 42.

In order to permit the sash to be swung open about the hinges it is necessary to release the sash from its connection with the counterweight 23 or 24, and in order to prevent at the same time said weight from falling down another hook 45 with a finger 46 is fastened to the stationary frame in such a position, that the hooks 42 and 45 will be located at the same height, when the female hinge parts on the sash are in engagement with the corresponding male parts. At the same time the fingers 44 and 46 will be arranged so, that the one is located right back of the other, as indicated in Figs. 4 and 5.

To transfer the holder plate from hook 42 to hook 45, when the sash is to be swung open, or vice versa, when the sash is to be slidably moved, a transfer plunger 47 is provided having a stem 48 pivotally connected to an arm 49 rigidly fastened to the cylinder 33. Said arm is arranged on the cylinder diametrically opposite of the above mentioned arm 35.

An angle shaped slot 50 is provided in the holder plate 25 as shown in Fig. 3 forming a finger 51 and a cam surface 52. The transfer plunger has a circular end flange 53 and spaced therefrom another circular flange 54. The plunger portion between said flanges is adapted to slide through the opening in the plate 25 between the finger 51 and surface 52, so that the flanges will be arranged one at each side of the plate.

Supposing the sash has been moved into its lowermost position, and the female hinge parts on the sash are engaged by the male hinge parts; the guide bar 39 is projected and in engagement with the groove 11 or 12; the holder plate 25 is held by the hook 42 on the sash, so that the counterweight is connected with the sash. If the sash then shall be swung open about the hinges, the key is inserted in the hole 34 in the cylinder 33, and said cylinder is rotated in such a manner, that the guide bar 39 will be retracted into the position shown in Fig. 1. Seeing that the arm 49 is arranged diametrically opposite of the arm 35, the plunger 47 will be projected by the same rotation of the cylinder. The flange 54 will engage the surface 52 of the plate 25 and will move said plate downwardly and side-

wardly, thereby releasing said plate from the engagement with the hook 42 on the sash, and moving said plate into position to be engaged by the hook 45. When the sash is swung open about the hinges, the plunger 70 passes between finger 51 and surface 52 of plate 25, and the holder plate will then be engaged by the hook 45. When the window sash is swung shut again the plunger enters again between the finger 51 and surface 52 75. When the cylinder 33 is rotated to project the guide bar 39 into engagement with the corresponding guide groove, the plunger is retracted, the flange 53 engages the surface 52 and moves the holder plate again downwardly and sidewardly, but this time into position to be engaged by the hook 42 on the sash, so that the sash is now again adapted to be slidably moved in the stationary frame. 85

What I claim as new and desire to secure by Letters Patent is:

1. In a window of the class described a stationary frame, a sash slidably arranged in said frame, a counterweight attached to 90 said sash, hinge parts on said sash, corresponding hinge parts on said frame, said parts being adapted to engage each other, when the sash is slidably moved into a predetermined position, guide ways in said stationary frame, guide plates on one side of said sash adapted to engage one of said guide ways, a guide bar on the other side of the sash, means for moving said guide bar into and out of engagement with a guide way opposite of the first mentioned guide way, a second counterweight, means for removably connecting said second counterweight to the sash, means on the stationary frame to hold said connecting means when removed from the sash, and means for moving said connecting means selectively into engagement with the sash and the stationary frame respectively. 105

2. In a window of the class described a 110 stationary frame, a sash slidably arranged in said frame, hinge parts on said frame, corresponding hinge parts on said sash adapted to engage said first mentioned hinge parts upon slidably moving the sash into 115 a predetermined position in the frame, a counterweight permanently connected to the sash, a second counterweight, a holder plate connected to said second counterweight, a hook on the sash adapted to engage said holder plate, a second hook on the stationary frame also adapted to engage the holder plate, and means on the sash for selectively moving the holder plate out of engagement with one of said hooks and into engagement 120 with the other hook. 125

3. In a window of the class described a stationary frame, a sash slidably arranged in said frame, hinge parts on said frame, corresponding hinge parts on said sash adapted 130

to engage said first named hinge parts upon moving the sash into a predetermined position in said frame, a counterweight permanently fastened to the sash, a second counterweight, a holder plate fastened to said second counterweight, a hook on said sash adapted to engage said holder plate, a second hook on said stationary frame also adapted to engage the plate, a guide way 10 in said stationary frame, a cylinder rotatably mounted in said sash, a guide bar, links movably connected to said cylinder and said guide bar, a plunger pivotally connected to said cylinder and adapted to engage said holder plate for moving it out of engagement with the one hook and into engagement with the other hook, the guide bar and the plunger moving in opposite directions upon rotation of the cylinder.

In witness whereof I have hereunto affixed my signature.

JOSEPH VIDINA.
